UNITED STATES PATENT OFFICE

NATHANIEL B. STONE, OF WASHINGTON, DISTRICT OF COLUMBIA

RECOIL BUFFER FOR CUTTER BARS

Application filed October 24, 1931. Serial No. 570,913.

This invention relates to agricultural machines wherein reciprocating cutter bars form a part thereof, the primary object of the invention being to improve generally the construction as described in my Patent No. 1,844,188, February 9, 1932.

An important object of the invention is to provide a buffer for reciprocating cutter bars wherein compression springs are used to absorb the severe shocks directed to the pitman and cutter bar mechanism when the cutter bar nears the end of its stroke.

A further object of the invention is the provision of yieldable means for overcoming the inertia of the blade and at the same time supply sufficient power to impart the initial movement to the cutter bar to start the cutter bar on its return stroke.

A still further object of the invention is to provide a device of this character wherein the springs of the mechanism are mounted to provide a small and compact structure, the springs being of the compression type and so arranged that the pressure thereof will be sufficient to require only slight movement of the springs and levers of the buffer to accomplish the purpose of the invention, thereby reducing wear on the springs and levers of the device to a minimum.

Another important object of the invention is the provision of a device of this character including levers having bearings of a construction to permit the levers to rock freely within the frame of the device by reducing friction between the bearings and levers.

With the foregoing and other objects in view which will appear as the description proceeds, the invention resides in the combination and arrangement of parts and in the details of construction hereinafter described and claimed it being understood that changes in the precise embodiment of the invention herein disclosed, may be made within the scope of what is claimed, without departing from the spirit of the invention.

Referring to the drawings:

Figure 1 is a fragmental plan view of the cutter bar of an agricultural machine showing the device constructed in accordance with

the invention as applied thereto, the cover of the device having been removed.

Figure 2 is a vertical sectional view through the cutter bar head and the buffer forming the essence of the invention.

Figure 3 is a sectional view through the device, parts thereof being shown in elevation.

Figure 4 is a sectional view through one end of the frame, showing one of the levers in elevation.

Figure 5 is a transverse sectional view through the buffer support.

Figure 6 is a fragmental elevational view of one of the levers, showing the manner of mounting the levers on the frame bearings.

Figure 7 is a perspective view of one of the bearings.

Figure 8 is a plan view of a modified form of the invention.

Figure 9 is a vertical sectional view through the frame, the springs and levers being shown in elevation.

Figure 10 is a vertical sectional view through the central portion of the device.

Figure 11 is a sectional view taken on line 11—11 of Figure 10.

Referring to the drawings in detail, the device as illustrated includes the usual cutter bar of an agricultural machine that comprises a finger bar 5 and sickle bar 6, the finger bar 80 being formed with a channel way in which the sickle bar 6 moves.

Rising from the rear edge of the finger bar, is a flange 8, which is formed with inclined side edges, the flange acting as a support for the buffer, to be hereinafter more fully described.

The buffer comprises a rectangular frame indicated generally by the reference character 9, which frame is provided with a depending flange 10 having inturned side edges providing flanges overlying the flange 8, to removably mount the buffer.

A notch is formed in one edge of the flange 8, and accommodates one end of the set screw 11 that is carried by the flange 10 to lock the buffer in position.

Rising from the frame is a striking lug 12 which may be struck by a suitable tool to drive the frame to its proper position.

Adjustable bars 13 are provided at each end of the frame 9, which bars 13 are held in position by means of the screws 13', shims 14' being positioned between the levers 18 and 5 frame 9, to the end that by adding or removing shims, the throw of the levers may be adjusted.

Extending longitudinally of the ends of the frame 9, and disposed in the inner surfaces 10 thereof are grooves 14 providing seats for the fulcrum bars 15 that are shown as provided with flat rear surfaces, and half round or contacting surfaces.

Teeth 16 extend from the fulcrum bars, 15 and fit within notches 17 of the levers 18. These levers 18 are formed preferably of sheet steel material, and are provided with wide upper portions 19 that taper off to substantially narrow portions 20, the portions 20 extending appreciable distances below the portions 19, where they will be engaged by the cutter bar head 21 as it reciprocates with the cutter bar.

The buffer also includes an outer expansion 25 spring 22, and inner expansion springs 23 and 24 respectively, the springs being nested or interposed in such a way that the forces thereof will be proportionate. The term expansion spring is used to describe a spring which is 30 normally compressed.

Caps 25 fit over the ends of the springs, and as shown are provided with transversely disposed notches that provide seats for the bearing bars 26, which bearing bars are also 35 provided with flat inner surfaces and half round outer surfaces, the lugs at the ends thereof being fitted in notches in the levers.

Due to this construction, it will be seen that the half round surfaces of the fulcrum 40 bars and bearing bars engage the flat inner and outer surfaces of the levers 18 permitting the levers to rock over the half round surfaces of the fulcrum bars and bearings to the end that friction between the fulcrum 45 bars, bearings and levers will be reduced to a minimum.

The teeth which operate in the notches, maintain the bearings and levers in their proper positions with respect to each other 50 and eliminate any possibility of the bearings or levers shifting laterally.

The levers 18 are formed with outwardly curved upper extremities 27 so constructed that a suitable tool may be positioned over 55 the outwardly curved ends of the levers and the springs may be compressed to permit the removal of the buffer proper, from its frame.

Hooks are formed at the lower ends of the levers, and are designed to engage a tool 60 such as shown in dotted lines in Figure 3 for holding the lower ends of the levers against outward movement, when the spring is tensioned to permit the removal thereof.

In order that the levers 18 may be made 65 of exceptionally light material, and at the

same time be sufficiently strong to withstand the action of the cutter head, reinforcing ribs 28 are provided, the ribs extending to points near the lower ends of the levers, as shown by Figure 4 of the drawings.

It might be further stated that the construction of the depending flange 10 is such that an opening is provided between the flanges 8 and 10, to permit a bar to be positioned therein so that a prying action of the bar will act to move the buffer upwardly and permit of its ready removal.

Due to the construction of the springs, a great pressure is exerted on the cutter head after each power stroke of the cutter head, to the end that the momentum of the cutter bar and cutter head is stored, and the power thus directed to the levers will be delivered to the recoil device in such a way that the cutter blade will be started on its return stroke.

In the modified form of the invention the frame is indicated by the reference character 5', and as shown the frame is formed with vertical grooves disposed intermediate the ends thereof, the grooves having inclined walls to accommodate the partition 6', which is formed with slanting faces to insure a wedge fit between the partition and frame of the device.

In this form of the invention a yieldable member indicated by the reference character 7', is positioned at each side of the partition, each yieldable member embodying nested expansion springs, the ends thereof being fitted in the caps 8'.

These caps 8' are identical in construction, with the caps 25, and support bearings 9' that engage the levers 10', the levers 10' being also engaged by the bearings 11' that are held in recesses in the ends of the frame of the device.

The levers 10' are substantially long and extend downwardly to points where they will be engaged by the cutter head of the cutter bar, to restrict momentum of the cutter head.

In order that the members 7' will be held against displacement, a pin 12' is provided, which pin is secured in the partition 6', the ends of the pin extending into the inner caps 8' of the springs 7'.

Due to this construction, it will be obvious that the required resiliency of the buffer is provided, but due to the fact that two yieldable elements are provided, the pulsations of the springs will be greatly reduced, thereby reducing wear to a minimum.

Having thus described the invention what is claimed is:

1. A buffer for reciprocating cutter bars, having heads comprising a frame to be mounted above the cutter bar head of a cutter bar, expansion springs mounted within the frame, and normally held under prede-

terminated tension levers disposed between the ends of the springs and the frame, the lower ends of the levers extending below the frame and adapted to be disposed in the path of travel of the cutter bar head, and said levers adapted to take up momentum of the cutter bar head.

2. The combination with the reciprocating cutter bar of an agricultural machine and the cutter bar head thereof, of a buffer comprising a frame, expansion springs mounted within the frame, levers pivotally mounted at the ends of the springs and urged outwardly towards the ends of the frame by the springs, said levers extending outwardly from the frame and lying in the path of travel of the cutter bar head to take up momentum of the cutter bar head and cutter bar connected therewith.

20 3. The combination with the reciprocating cutter bar of an agricultural machine, and the cutter bar head thereof, of a buffer comprising compressible means including levers normally urged outwardly by the compressible means and said levers lying within the path of travel of the cutter bar head and moved laterally by the cutter bar head to take up momentum of the cutter bar head.

30 4. The combination with the cutter bar head of an agricultural machine, of a buffer including a frame, a plurality of nested coiled springs mounted within the frame, rockable levers mounted between the ends of the springs and the frame, said springs normally urging the upper ends of the levers outwardly said levers extending downwardly below the frame and lying within the path of travel of the cutter bar head, to take up the momentum of the cutter bar head, and cutter bar connected therewith, and means for adjusting the throw of the levers.

35 5. The combination with the cutter bar head and cutter bar of an agricultural machine, of a buffer comprising a frame, expansion springs mounted within the frame and normally held under predetermined tension, levers mounted within the frame, bearings at the ends of the springs and engaging the levers, bearings on the frame and engaging the levers, the last mentioned bearings lying in a plane below the first mentioned bearings to force the lower ends of the levers inwardly, and said levers lying within the path of travel of the cutter bar head, to take up momentum of the cutter bar head.

40 6. The combination with the cutter bar head and cutter bar of an agricultural machine, of a buffer comprising a frame, expansion springs mounted within the frame and normally held compressed under a predetermined tension, bearings removably mounted at the ends of the springs, bearings mounted on the frame, said bearings having rounded outer surfaces and substantially flat inner surfaces, levers having flat surfaces

mounted between the bearings at each end of the frame, the rounded surfaces of the bearings engaging the flat surfaces of the levers, and said levers arranged to co-act with the cutter bar head, to store the momentum of the cutter bar.

7. A buffer for reciprocating cutter bars having heads comprising a frame, expansion springs mounted within the frame and normally held under tension, levers mounted between the ends of the springs and frame, bearings disposed between the springs and levers, bearings disposed between the levers and frame, said bearings having rounded surfaces engaged by the levers, said levers adapted to rock on the bearings, and said levers extending into the path of travel of the cutter bar head to take up movement thereof, and means for securing this device to the machine.

8. A buffer for reciprocating cutter bars having heads, comprising a frame, nested expansion springs mounted within the frame, levers mounted within the frame and held within the frame by the outward pressure of the springs, the lower ends of the levers lying within the path of travel of the cutter bar head of the cutter bar with which the buffer is used to absorb momentum of the bar, bearings supported by the frame and ends of the springs and over which the levers move.

9. The combination with the cutter bar head of an agricultural machine, of a buffer mounted in close relation to the cutter bar head, said buffer comprising nested expansion springs, levers pivotally mounted intermediate their ends and held in position by the outward pressure of the springs, said springs acting against the upper ends of the levers to normally urge the lower end of the levers inwardly, and the lower ends of the levers lying in the path of travel of the cutter bar head to regulate movement of the cutter bar head.

10. The combination with the cutter bar head of an agricultural machine, of a buffer mounted near the cutter bar, said buffer comprising a frame, coiled springs supported within the frame, caps at the ends of the springs, said caps having recesses, bearings in the recesses, said bearings having lugs at their ends, levers disposed between the ends of the springs and the frame, bearings carried by the frame, said bearings having lugs at their ends, said levers having recesses to receive the lugs to prevent lateral movement of the bearing members, and said levers extending in the path of travel of the cutter bar head with which the device is used to restrict momentum thereof.

11. In a buffer for reciprocating cutter bars, a support, expansion springs mounted on the support, caps fitted over the ends of the springs, bearings mounted on the caps
